TUBING ANCHOR

Jeddy D. Nixon, New Braunfels, Tex., assignor to
 Wilson Foundry & Machine Company, Houston,
 Tex., a corporation of Texas

Application April 22, 1949, Serial No. 89,053

6 Claims. (Cl. 166—1)

1

This invention relates to new and useful improvements in tubing anchors.

One object of the invention is to provide certain improvements over the tubing anchors set forth in Patents 1,941,813, issued January 2, 1934, and 1,972,408, issued September 4, 1934.

A particular object of the invention is to provide an improved slip for the anchor which may be successfully drop-forged and heat treated, thereby giving it the required tensile strength and toughness, and permitting it to be turned down to fit in well pipes of different diameters, as well as making for less expensive manufacture by reducing the amount of machining and finishing required.

Another object of the invention is to provide an improved anchor having a cylindrical body formed with elongate bosses and valleys between said bosses, whereby the slips may be formed with inwardly directed wings extending into the valleys and holding the slips against circumferential creeping and more particularly, each wing giving sufficient bulk or cross-sectional area to provide axial cores which are not reached when the slip is heat treated; such cores providing tough centers and enhancing the tensile strength and toughness of the slip.

A construction designed to carry out the invention will be hereinafter described together with other features of the invention.

The invention will be more readily understood from a reading of the following specification and by reference to the accompanying drawings, wherein examples of the invention are shown, and wherein:

Fig. 1 is a view partly in elevation and partly in section of a tubing anchor constructed in accordance with the invention,

Fig. 2 is a horizontal cross-sectional view taken on the line 2—2 of Fig. 1,

Fig. 3 is a vertical sectional view through one of the slips,

Fig. 4 is an inner elevation of one of the slips,

Fig. 5 is a horizontal cross-sectional view taken on the line 5—5 of Fig. 4,

Fig. 6 is a plan view of one of the slips, and

Fig. 7 is a partial vertical sectional view of a modified form of the invention.

In the drawings the numeral 10 designates a tubular insert or mandrel which has a screw-threaded pin 11 at its lower end and an internally screw-threaded box 12 at its upper end, whereby it may be connected in a string of well tubing in the usual manner. At the medial portion of the mandrel a cylindrical enlargement or body 13 is formed integral therewith and connected at each end with the pin and box by annular shanks or necks 14.

2

At the top and bottom the body has annular, beveled seats 15 inclined toward the necks. At the upper end of the pin an annular collar 16 is made integral with the lower neck 14. At the bottom of the box 12 an annular shoulder 17 is provided. The distance between the upper seat 15 and the shoulder 17 is substantially the same as the distance from the bottom seat to the collar 16. The necks with the collar and shoulder constitute annular grooves 18.

Quadrilateral, segmental slips or jaws 19 surround the body 13 and are of particular construction. A description of one of the slips will suffice for all of them. It will be observed that the body 13 is formed with four equally spaced vertical bosses 20 having vertical valleys or recesses 21 therebetween. The outer faces 22 of the bosses are curved transversely, preferably concentric to the outer faces of the slips.

20 Each slip 19 is formed with a transversely curved inner top and bottom surfaces 23, substantially concentric to the necks 14 and with a vertical pocket or sump 24 receiving one of the bosses 20. The bottom 25 of the sump or inner face of the slip is struck on an arc complementary to the face 22 of the boss so as to intimately engage said face, whereby an inward transverse thrust sustained by the slip is absorbed by the boss and distributed over the broad area of said boss.

25 30 The sump 24 is flared outwardly from its face 25 to conform to the seats 15 and the sides of the boss. However, the sump is considerably larger so that when the faces 22 and 25 are in contact, no other portions of the slip are intentionally in contact with any part of the body, except that the slip may shift vertically and seat on one of the seats 15 or it may shift circumferentially and contact one side of the boss 22. The inner surfaces 23 of the slip do not engage the necks 14. This construction provides for a free radial movement of the slip and as before stated, imparts its entire inward thrust to the face 22 of the boss.

35 40 45 The slip is formed with outer horizontal curvilinear teeth 26, as in my former Patent 1,941,813, these teeth are V-shaped in cross-section and because of their close spacing, as well as their shape, may be referred to as level threads. The teeth of the slip are disposed in such a transverse arc that when all of the slips are fully expanded, they will be in an annulus substantially concentric to the casing or pipe, in which the anchor is located, so as to bite uniformly into the inner wall of said casing or pipe.

50 55 As is best shown in Figs. 2, 4 and 5, the slip at each side of its sump 24 has inwardly directed vertical wings 27, the inner edges of which are

offset outwardly from the top and bottom surfaces 23 and extend into the valleys 21. Each wing is flared outwardly or wedge-shaped in cross-section. It is preferable to drop forge the slip and to heat treat it to the required hardness. Since heat treating penetrates the surface of the metal, it will be seen that because of the transverse or cross-sectional area of each wing, sufficient body or bulk is provided, whereby a core or axial area is provided in the center of the wing which is not hardened and this tough center enhances the tensile strength of the slip. 10

The wings 27 not only increase the strength of the slip, but permits the outer surface of the slip to be turned down to fit a smaller diameter casing or pipe and the entire tooth surface to be heat treated. The wings also hold the slip against undesired circumferential movement. By drop-forging the slip and its loose mounting on the boss 20, the only machining required is that of the teeth. 15

Each slip has reduced integral segments 28 at its top and bottom above and below its teeth. Each segment has a groove 29 shaped to receive a coiled spring ring 30 so that when the four slips are assembled on the bosses, said springs will hold them in position and at the same time permit radial expansion. Below its groove, each segment is beveled as indicated at 31. When the slips are in position on the body 13, the segments form collars and the grooves are substantially annular. 20

Since the expansion of the slips 19 is hydraulic, cylindrical bores 32 are formed in each boss, one bore being spaced above the other bore and each bore having an annular stop shoulder or abutment 33 at its inner end surrounding an inlet opening 34 from the bore 35 of the mandrel 18. A solid cylindrical piston 36 has a snug sliding fit in each bore 32 and is of such length that when its inner end engages the abutment 33, its outer end is flush with the face 22 of the boss; said outer end being finished to conform to the face 22. 25

Each piston is sealed in its bore by a circular elastic packing ring, known to the oil industry as an O-ring. It is obvious that when the inner ends of the pistons are subjected to fluid pressure, sufficient to overcome the spring rings 30, said pistons will be forced outwardly, thereby displacing the slips 19 outwardly. When the fluid pressure is sufficiently reduced, the rings 30 will retract the slips and the pistons. 30

Anchors of this type are particularly adapted for use with reciprocating well pumps and because of the V-shaped teeth, will hold the tubing and working barrel against both upward and downward movement or creeping. The anchor of course has many uses. By being able to turn down the slips 19 to reduced diameters, the number of sizes in which the anchor must be made is reduced. The provisions of the wings, whereby the web of the slip between said wings may be reduced in thickness, due to turning the face down to a reduced diameter without seriously weakening the slip, is quite an advantage. 35

In the prior patents hereinbefore referred to, the slips were comparatively thin and of uniform thickness. When such slips were heat treated they had a tendency to become brittle and did not lend themselves to machining to reduce their diameters. By employing the wings the slips may be made thicker and the circumferential area which contacts the bosses is less 40

than in the slips of the prior patents. This gives space for the valleys and the wings. 45

In Fig. 7 I have shown a modified form of the invention in which each boss 20 is formed with a circumferential groove 37 between its bores 32 for loosely receiving an arcuate rib 38 in the sump 24. This rib serves the same purpose as the wings 27 in providing a core in connection with the heat treating of the slip. 50

The foregoing description of the invention is explanatory thereof and various changes in the size, shape and materials, as well as in the details of the illustrated construction may be made, within the scope of the appended claims, without departing from the spirit of the invention. 55

What I claim and desire to secure by Letters Patent is:

1. A tubing anchor including, a tubular mandrel adapted to be connected in a well tubing and having a body intermediate its ends provided with elongated bosses and valleys therebetween, radially movable slips on said bosses having thickened wings disposed in the valleys, piston means mounted in the bosses of the body exposed to the bore of the mandrel and engaging the slips, and retaining means holding the slips in assembled relation to the body. 20

2. A tubing anchor as set forth in claim 1, wherein the bosses and the slips have curvilinear contacting areas surrounding the piston means between the valleys and wings. 25

3. A tubing anchor as set forth in claim 1, wherein the wings are wedge-shaped and each wing provides an axial unhardened core when the slip is heat treated. 30

4. A tubing anchor including, a tubular mandrel having means at each end for connecting it in a string of well tubing, an elongate body intermediate the ends of the mandrel having elongate bosses and elongate valleys between said bosses, each boss having spaced cylindrical bores extending radially therein and open to the bore of the mandrel, elongate cylindrical pistons fitting in the bores of the bosses and surrounded by packing rings, elongate slips having sumps receiving the bosses and the pistons, elongate wings on the slips on each side of the sumps extending into the valleys, and spring rings surrounding the slips and holding them on the bosses. 40

5. A tubing anchor as set forth in claim 4, wherein the outer faces of the bosses and bottoms of the slip sumps are concentric and in contact and said sumps are larger than the bosses to provide freedom of movement of said slips. 45

6. A tubing anchor as set forth in claim 1, wherein each boss has a circumferential groove and each slip has a transverse arcuate rib engaging in said groove. 50
